DESIGN.

P. GROEBER.
WALL AND CEILING COVERING.

No.19,620.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,620, dated January 28, 1890.

Application filed December 26, 1889. Serial No. 335,051. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design represents an upright 1, with branched ornament in top, and two scrolls 2 and 3, one on each side, terminating with a rosette. A thin scroll also branches on each side to the top. There

15 are also smaller uprights 4, having the same ornament on top as the last, but without the two large scrolls with rosettes. It has, how-

ever, two small scrolls 5 and 6, one on each side, and 7 and 8. The groundwork is filled in with fine lines and scrolls 9. Between the 20 uprights are horizontal bars 10, forming panels 11, each with a double-scroll ornament. The lower panels are also ornamented with scrolls 12.

What I claim is—

25 A design for a wall and ceiling covering herein shown and described, consisting of a border having uprights with scrolls, ornamented panels, and a groundwork filled in with fine lines and scrolls.

PAUL GROEBER.
